ANTENNA

George A. Jarvis, Cambridge, Mass., assignor, by
mesne assignments, to the United States of
America as represented by the Secretary of War

Application August 30, 1945, Serial No. 613,602

4 Claims. (Cl. 250—33)

1

This invention relates to antennas for high frequency communication systems and more particularly to antennas such as are suitable for use as "beacons."

The principal object of the invention is to provide an antenna system adapted to produce a beam of radiant energy having practically no horizontal directivity but having a certain amount of vertical directivity, the vertical directive pattern having preferably a maximum at some small angle with the horizontal.

Another object of the invention is to provide an antenna having a radiation pattern that is approximately circular in a horizontal plane passing through the antenna (uniform in azimuth) and that has a substantial range in the vertical respect.

In general, the present antenna comprises a radiating element adapted to be mounted directly upon an associated feeder transmission line of the enclosed type which may be a coaxial conductor or a hollow pipe wave guide. The element comprises a plurality of dipoles, the number being three in the illustrated preferred embodiment. The dipoles are excited and supported by supporting members extending outwardly from the associated transmission line, the dipoles being mounted at the ends of the supporting members. The dipoles may be axially curved in such manner that their projections on a horizontal plane substantially define a circle with only relatively small interruptions.

The antenna element described generally above may be used singly as an antenna, or a plurality of such elements may be arranged on a transmission line to constitute a linear array antenna.

In the drawings:

Fig. 1 is an elevation view of an antenna according to one embodiment of the invention;

Fig. 2 is a sectional view of the same along the line 2—2 of Fig. 1;

Fig. 3 is a partial sectional view similar to that of Fig. 2 showing a modification of the invention on a reduced scale; and

Fig. 4 is a partial sectional view similar to that of Fig. 3 showing another modification of the invention.

Figs. 1 and 2 illustrate one form of antenna system, according to the invention, and show two antenna radiating elements 10 mounted on a transmission line 11. Line 11 is of the coaxial conductor type having a central conductor 12 and a spaced outer conductor 13 suitably disposed in a vertical position. While two elements 10 are illustrated, it will be understood that, in the

preferred embodiment, only one such element may be used. For simplicity of description, the invention will more particularly be described hereinafter to one element 10 although it will be understood that more than two or more such elements may also be utilized, according to the invention, depending upon the radiation pattern desired. Transmission line 11 is fed from below by means not shown and may be terminated at the upper end by absorbing material shown generally at 14 or by a tuning plunger 15, or both.

Radiating element 10 comprises a plurality of pairs of dipole supporting arms, each arm being of the order of a quarter wavelength, the two arms of each pair extending in spaced parallel relation as shown in Fig. 2, the spacing between the pairs of arms at their point of connection to the dipoles being preferably less than a wavelength of the energy at the operating frequency. Three pairs of arms are shown in the drawing extending away from line 11 and are generally in a plane normal to the axis of line 11. One such pair comprises arms 16 and 17 carrying at their outer ends dipole sections 18 and 19, respectively. As will be understood, sections 18 and 19 constitute one dipole. Similarly, arms 16', 16'', and 17' and 17'' have dipole sections 18', 18'', 19' and 19'', respectively. Thus as illustrated, the antenna element described comprises three dipoles uniformly spaced around a feeder transmission line.

The dipole comprising sections 18 and 19 is excited by means of supporting arm 16 which is disposed substantially radially of the antenna element 10 and extends through an aperture or slot 20 in the outer conductor 13 into the region of propagation within the transmission line 11. As shown in Fig. 2, arm 16 is connected to central conductor 12 at 21 for direct coupling although capacitive coupling may also be utilized as explained hereinafter.

Supporting arm 17 is disposed parallel to arm 16 and is directly connected to and supported on the outer conductor 13. Thus arm 17 will be disposed substantially tangentially to outer conductor 13 or at an acute angle ϕ with a line T tangent to the outer surface of conductor 13 at the point of connection.

The dipole antenna element 10 is preferably disposed with the plane through the three dipoles horizontal. Also, the dipole sections 18, 18', 18'', 19, 19', and 19'' may have a curved configuration so that the projection of three dipoles, as shown in Fig. 2, on a horizontal plane 55 substantially defines a circle preferably con-

centric with line 11. This provision, in general, determines the uniform azimuth characteristic. It also reduces the size of the antenna element and permits accommodation of a tubular housing for sealing the device in a weatherproof or pressure-proof manner.

In the modification of the invention shown in Fig. 3, the antenna element 10 is excited by a hollow wave guide type transmission line. For example a circular wave guide excited in the radial E-vector mode ($TM_{0,1}$) may be used as the source of excitation. Instead of the supporting arm 16, being connected to a central conductor as described with reference to Fig. 2, a dipole supporting arm 22 extends into wave guide 23 through aperture or slot 24 along the direction of the E-vector for a distance suitable for desired "pick-up" of energy. If desired, a suitable probe or pick-up loop 25 may be carried by or connected to the inner end of arm 22. If desired, the amount of pick-up may be varied by adjusting the distance which each probe or loop 25 extends into wave guide 23. In fact, if desired, an unsymmetrical pattern may be obtained in the plane passing through the three dipoles by unbalancing the respective distances which arms 22 or probes 25 extend into the wave guide 23. As will be understood, this means of excitation may also apply to the coaxial conductor type transmission line, as described with reference to Fig. 2. Thus arms 16, 16' and 16'' need not be directly connected to central conductor 12 but may extend the desired distance into the space in the coaxial line between the central and outer conductors 12 and 13, for capacitive coupling.

In order to support arm 22 of Fig. 3 or arm 16 of Fig. 2 when the latter is not directly connected to the central conductor 12, it is necessary to provide supporting means. One such means is shown in Fig. 4 and comprises a dielectric member 26 in place of slots or apertures 24 or 20 of Figs. 2 and 3 and secured to the outer wall of the wave guide 23 or outer conductor of the coaxial line. The dielectric member 26 has an aperture therethrough, which may be threaded, for receiving arm 22 or 16 whereby arm 22 or 16 is supported by the dielectric member and is insulated from the outer conducting wall of the wave guide 23 or of coaxial line 11.

It will be understood that the antenna, according to this invention, in its contemplated vertical position with the dipoles uniformly spaced about the transmission line and uniformly excited, is adapted to radiate energy in a pattern which is substantially circular in a horizontal plane (uniform in azimuth) and in a substantially uniform and symmetrical pattern in a vertical plane.

While there has been described what is at present considered preferred embodiments of the invention, it will be obvious to those skilled in the art that various changes and modifications may be made therein without departing from the spirit of the invention.

What is claimed is:

1. An antenna construction, adapted for use

with an enclosed transmission line, for high frequency electromagnetic energy, comprising three curved dipoles uniformly spaced about said line, each of said dipoles comprising a pair of spaced dipole sections lying in a plane perpendicular to the longitudinal axis of said line, and means for supporting and exciting each of said dipoles, each of said means comprising a pair of spaced parallel supporting arms having a length substantially equal to a quarter of the wavelength of the exciting energy, and extending outwardly from said line, one of said dipole sections being electrically connected and carried at the outer end of each of said supporting arms, one of each pair of supporting arms being connected to the outer conductor wall of said line at a point adjacent one of three apertures and extending substantially tangentially from said outer conductor, the other of each pair of supporting arms extending substantially radially of said line through the corresponding aperture in said wall and into the region of propagation within said line, the inner end of each of said radially extending supporting arms being electrically coupled to said energy in said line whereby said dipoles are excited by said energy.

2. An antenna construction as claimed in claim 1 wherein each of said dipole sections is so disposed that the curved configuration of said three dipoles projected on a plane perpendicular to the axis of said line substantially defines a circle about said axis.

3. An antenna construction as claimed in claim 1 adapted for use with a coaxial cable transmission line having a central conductor and a spaced outer conducting wall, wherein the radially extending supporting arms have their inner ends electrically connected to and carried on said central conductor.

4. An antenna construction as claimed in claim 1 adapted for use with a hollow pipe wave guide transmission line, wherein coupling means are provided at the inner ends of the radially extending arms of said pairs of supporting arms whereby said dipoles are excited by the energy in said line and wherein dielectric means are provided for supporting said radially extending arms on said wave guide while insulating said radially extending arms from the wall of said wave

guide.
